UNITED STATES PATENT OFFICE.

HELGE A. BORRESEN, OF CHICAGO, ILLINOIS, ASSIGNOR TO THE C. H. HANSON COMPANY, OF CHICAGO, ILLINOIS, A CORPORATION OF ILLINOIS.

PLATE MOUNTING.

Application filed June 6, 1925. Serial No. 35,431.

My invention relates to a plate mounting, and more particularly to means for mounting a plate, such as a name plate, on a supporting material.

5 It is the purpose of my invention to provide means for mounting a plate on a supporting material, said plate and said means being made of a single piece of sheet material with the edges thereof embedded in 10 the supporting member.

It is a further purpose of my invention to provide means for holding the plate in position on the supporting member, comprising 15 a plurality of prongs that engage with the supporting member, said prongs preferably bending as the same are forced into the material upon which the plate is mounted so as to assume a hook-like form. The mounting member is preferably provided 20 with recesses for receiving the prongs, said recesses being provided with guiding surfaces whereby the prongs are bent in the desired direction.

The plate is preferably pressed into the 25 material, or forced into engagement with the material by pressure, and the supporting material is preferably, although not necessarily, provided with a groove into which the peripheral edge of the plate fits 30 when the same is forced into engagement with the supporting material.

It is another object of my invention to 35 provide a plate, such as a name plate, that can be made of very light material, said plate being preferably supported in face-to-face engagement with the supporting member when in operative position. Preferably, the hook prongs are provided, but in some cases it may be desirable to provide tubular 40 prongs. The material of the supporting member, if wood or some similar material, will then enter the tubular portions of the prongs to further aid in holding the parts in assembled relationship. Instead of providing prongs, the edge or flange that is 45 turned toward the supporting member may be serrated so as to bite into the material and bend into a hook-like form to hold the plate in position on the mounting or supporting member.

Other objects of the invention will appear as the description of the accompanying drawing proceeds. However, I desire to have it distinctly understood that I do not

intend to limit myself to the exact details shown or described, but that I intend to include as part of my invention all such obvious changes and modifications of parts as would occur to a person skilled in this art and as would fall within the scope of 55 the claims.

In the drawings,—

Fig. 1 is a side elevation of one of my improved plates, detached;

Fig. 2 is a plan view of a fragment of the 65 supporting member with the plate in position thereon;

Fig. 3 is a section taken substantially on the line 3—3 of Fig. 2;

Fig. 4 is a plan view of a fragment of the 70 supporting member showing the same before the plate is assembled therewith;

Fig. 5 is a section taken on the line 5—5 of Fig. 4;

Fig. 6 is a section taken on the line 6—6 75 of Fig. 4;

Fig. 7 is a view similar to Fig. 3, of a modified form of the invention;

Fig. 8 is a view similar to Fig. 3, of a further modification of the invention; 80

Fig. 9 is a view similar to Fig. 1, of the plate used in the form shown in Fig. 7;

Fig. 10 is a bottom plan view of a plate provided with tubular prongs;

Fig. 11 is a side elevation thereof; 85

Fig. 12 is a section taken on the line 12—12 of Fig. 11;

Fig. 13 is a view similar to Fig. 2, of another form of plate;

Fig. 14 is a view similar to Fig. 2, of still 90 another form;

Fig. 15 is a section similar to Fig. 3, showing the plate mounted on a metallic supporting member;

Fig. 16 is a plan view of a further modification; 95

Fig. 17 is a side elevation of the plate shown in Fig. 16; and

Fig. 18 is a side elevation of a further 100 modification.

Referring in detail to the drawings, in Figs. 1 to 3, inclusive, is shown a plate member 20, which is provided with a body portion 21 from which the prongs 22 depend. The plate member 20 is mounted upon a 105 supporting member 23, which is more clearly shown in Figs. 4 to 6, inclusive, and which is provided with a groove 24

corresponding substantially in outline to the downturned edge or flange 25 on the plate 20. The groove 24 is provided with a curved inner face 54, and a straight outer face 55, which causes the flange 25 to assume a concave form in cross section when the member 20 is pressed into engagement with the member 23. The member 23 is further provided with a plurality of recesses 26 extending from the groove 24, which have substantially straight outer walls 27 and curved inner walls 28. It will be further noted that the prongs 22 are slightly curved inwardly between the body portion 21 and the extremities thereof. The groove 24 and the recesses 26 are formed in the supporting member 23 in any desired manner, preferably by means of a die. The plate 20 is preferably forced into engagement with the supporting member 23 by means of a press. When the plate 20 is pressed into engagement with the member 23, the prongs 22 will curve into the shape shown in Fig. 3, thus becoming hook-like holding members or holding prongs, this being due to the fact that the curved faces 28 act as guiding faces to direct the bending of the prongs when pressure is applied to the plate 20. The plate 20 is forced down until the body portion 21 thereof is in face-to-face engagement with the face 29 on the supporting member 23 defined by the groove 24. When this occurs the downturned edge or flange 25 will be seated in the groove 24. Thus no sharp edges will be exposed, the hook prongs will firmly hold the plate in position on the supporting member, and, moreover, it will be difficult to remove the plate from the supporting material without doing considerable damage to both the plate and the supporting material, because it will be impossible to get a tool under the edge of the plate.

Instead of turning the prongs inwardly on a curve, as are the prongs 22 in Fig. 1, and again outwardly toward the free ends thereof, the prongs may be inclined inwardly from the body portion to the outer edge thereof, as shown in Fig. 9, in which the prongs are designated by the numeral 22' and the plate by the numeral 20'. The plate 20' is provided with a depending peripheral flange 25', which seats in a groove in the member 23', shown in Fig. 7, in a similar manner to that in which the flange on the member 20 is received in the groove of the member 23 in the previously described form. The member 23', instead of being provided with recesses with curved guide faces, is provided with the recesses 26' having the straight outer faces 27' and the inclined or beveled inner faces 28'. The prongs, when the plate 20' is pressed into engagement with the member 23', will turn inwardly at a sharper angle than that which they originally have before the plate 20' is engaged

with the member 23', thus forming hook-like prongs or holding members, this being due to the provision of the inclined guiding faces 28', down which the ends of the prongs slide as the plate 20' is pressed into engagement with the supporting member 23'. 70

In Fig. 8, the member 20 is shown as being pressed into engagement with a supporting member 30, the curved prongs 22 engaging with recesses in the member 30 having inclined inner faces 31 and curved outer faces 32. This causes the hook prongs 22 to bend into a double or reverse curved form when the plate 20 is pressed into engagement with the member 30, as will be clear from Fig. 8 75

In Figs. 10 to 12, inclusive, still a different form of plate 33 is shown, in which the prongs 34 provided thereon are preferably tubular, as will be clear from Figs. 11 and 12. From Fig. 12 it will be seen that concavities or pockets 35 exist within the prongs 34, into which the material of the supporting member, into which said members 34 are pressed, will enter to thus cause the prongs to interlock with the material. The body 85 portion of the member 33 is indicated in Fig. 10 by the numeral 36, and said member is further provided with a peripheral downturned edge or flange 37, as in the other forms. 90

While the plates are shown as being circular in Figs. 1 to 12, inclusive, these obviously can be made of any desired shape, the plate 38 in Fig. 13, mounted on the supporting member 39, being made in the form 100 of a shield, and the prongs 40 thereon being formed out of such portions of the material as would otherwise be wasted in forming the shield 38. 95

In Fig. 14 an oval plate 41 is shown 105 mounted on the supporting member 42 by means of the prongs 43, which are also cut out of the material from which the blank is made at such places that no extra material will be required for making the prongs. 110

While the plate-like members have been shown in all the forms of the invention described above as being mounted on some relatively soft material, such as wood, the plates can be applied to metallic surfaces as 115 well. In Fig. 15, the plate 20' is shown as being applied to a sheet-metal supporting member 44, which is provided with the openings 45 and the curved guiding fingers 46 below the openings 45 formed out of the material punched out of the openings 45. The hook portions 22' engage with said curved guide fingers 46, the ends thereof moving along the curved surfaces of the guide fingers as the plate 20' is pressed into face-to-face engagement with the supporting member 44, the prongs 22' being of such a length that the ends 47 thereof will engage with the inner face of the supporting member 44 120 inwardly of the openings 45. 125

Instead of providing distinct prongs on the plate member, a plate such as the plate 48, shown in Fig. 17, may be provided, said plate having the body portion 49, which is flat, and which is adapted to lie in face-to-face engagement with the supporting member 50, and further having a downturned peripheral edge portion or flange 51 that is provided with a toothed or serrated edge 52, the projections formed by the teeth 52 acting as prongs to hold the plate-like member 48 in position on the supporting member 50. The supporting member 50 is provided with a groove corresponding to the groove 24 in the member 23. The members 52 will bend into outwardly curved hook form when pressed into the supporting member 50 to thus firmly interlock the plate 48 with the supporting member 50, throughout the entire circumference of said plate.

In Fig. 18 a plate 20" is shown that has no flange thereon, but is merely provided with prongs 22" that engage with the supporting member in substantially the same way as the prongs 22 in Fig. 3.

Having thus described my invention, what I desire to claim and secure by United States Letters Patent is:

1. The combination with a supporting member provided with a groove, of a plate mounted thereon, said plate having a downturned edge seated in said groove, and members on said plate extending beyond said downturned edge to embed themselves in said supporting member.

2. The combination with a supporting member provided with a groove, of a plate mounted thereon, said plate having a down-

turned edge seated in said groove, and members on said plate extending beyond said downturned edge adapted to embed themselves in said supporting member, said supporting member having recesses opening into said groove and receiving said last members.

3. The combination with a supporting member provided with a groove, of a plate mounted thereon, said plate having a downturned edge seated in said groove, and prongs on said plate extending beyond said downturned edge adapted to embed themselves in said supporting member, said supporting member having recesses opening into said groove and provided with guiding faces for said prongs.

4. The combination with a supporting member provided with a groove, of a plate mounted thereon, said plate having a downturned edge seated in said groove, and tapering prongs on said plate forming integral extensions of said edge and adapted to embed themselves in said supporting member, said prongs being curved transversely of their length.

5. The combination with a supporting member, of a plate having a downturned peripheral edge seated in said supporting member, and hook-like projections on said plate engaging said supporting member beyond said edge, said supporting member having guiding faces for bending said projections into hook-shape.

In witness whereof, I hereunto subscribe my name this 2nd day of June, A. D. 1925.

HELGE A. BORRESEN.
